UNITED STATES PATENT OFFICE.

JOHN J. BURWELL, OF COVINGTON, KENTUCKY.

STEAM-GENERATOR.

SPECIFICATION forming part of Letters Patent No. 443,354, dated December 23, 1890.

Application filed April 8, 1890. Serial No. 347,065. (No model.)

To all whom it may concern:

Be it known that I, JOHN J. BURWELL, of Covington, in the county of Kenton and State of Kentucky, have invented a new and useful 5 Improvement in Steam-Generators, which improvement is fully set forth in the following specification and accompanying drawings, in which—

Figure 1 is a vertical longitudinal section 10 of a locomotive-boiler provided with my improved device; Fig. 2, a vertical cross-section of the same on line *x x* in Fig. 1, and Fig. 3 a vertical cross-section on line *y y* in Fig. 1.

My invention relates to improvements in 15 steam-generators of the class generally used in connection with locomotive-engines. My object is to provide a simple and practical device, whereby a more thorough combustion of the fuel is secured, the flues and their connections rendered more durable, a larger heating-surface obtained without increasing the size or number of the flues, a decreased grate-surface, and a consequent saving of fuel and labor, together with immunity from destructive 25 fires caused by sparks from the smoke-stack.

My invention consists in dividing the flues into three groups or sections and arranging the groups in a vertical series with intermediate 30 regenerative chambers between the sections, whereby the gases are replenished by the admission of a suitable supply of air during their passage from one series of flues to another. By this plan the heat necessarily 35 traverses the body of water thrice instead of only once, as in boilers constructed in the usual manner.

Referring to the accompanying drawings, A designates the shell of a locomotive-boiler; B, the fire-box, from which the flames pass into the upper group of flues C, and thence into the chamber D, which is provided with an aperture E for the admission of oxygen, the supply of which is regulated by a 45 suitable valve having a connecting-rod or other appliance (not shown) extending to the cab. The heat, being thus replenished, passes through the middle group of flues F and into the second regenerative chamber G, where 50 it receives an additional supply of oxygen through the valve H. The lowest group of flues I receives and conveys the products of

combustion into the smoke-box J, where it meets the exhaust and is discharged through the smoke-stack in the usual manner. If preferred, the lowest group of flues may extend only to the dotted line K; but if the construction of the boiler should permit, it is desirable that they be extended forward, as shown in the drawings. 55

The operation of the device will now be explained. When the flames pass through the upper group of flues and reach the chamber D, the natural upward tendency of the heat temporarily retards the current. The surplus carbon is thus permitted to intermingle with the oxygen admitted by the valve E. The flame is thus re-enforced and enters the middle group of flues and passes into the second regenerative chamber G, where the re-enforcing process is repeated with an important additional advantage. It is a well-known fact that a large portion of fuel is wasted in boilers having only one set of flues. Unconsumed fragments of coke are carried through 65 by the force-draft and thrown out of the smoke-stack. Bridges and other valuable property are thereby ignited and destroyed. In order to obviate such danger and secure complete combustion, the second chamber G extends 70 downward below the plane of the lowest group of flues and forms a pocket. The draft being partially checked by the admission of air, as hereinbefore described, the particles of carbon or coke fall into the receptacle and 75 are consumed, and the additional heat thus produced is utilized by the adjacent water-spaces M M. The ashes and other residuum may be removed through the trap-door L.

It is furthermore understood that in ordinary boilers, which have no means of distributing the heat uniformly, the tubes are liable to buckle and spring leaks, especially when the heat is first applied. In this device the heating process is necessarily more 80 gradual and uniform, and the tubes are not subjected to sudden and unequal strains. 90

What I claim as new is—

1. A steam-generator of the locomotive type having the regenerative chambers D and 100 G, the latter at the rear of the fire-box and its heat utilized by the adjacent water-chambers M M, and both of said chambers provided with apertures for the admission of

air, in combination with horizontal flues arranged in three vertically-disposed groups and communicating, as described, with said chambers and with the smoke-stack, as and 5 for the purposes set forth.

2. In combination with the fire-box B and the regenerative-chamber G at the rear, surrounded, as described, by the water-spaces

M M, the group of pipes C, F, and I, regenerative chambers D and G, suitable provision being made for the admission of air to the said chambers D and G, substantially as set forth.

3. In a steam-boiler as described, the chamber G at the rear of the fire-box, having adjacent thereto the water chambers or spaces M 15 M and extending down to form a pocket, and having therein a valve by which said pocket can be cleaned, substantially as set forth.

4. In a steam-boiler, a chamber at the rear of the fire-box, with which the flues carrying the smoke and other products of combustion communicate, extending below the said flues so as to form a pocket for cinders, &c., and provided with a valved opening by which it can be cleaned out, all as and for the purposes 20 25 set forth.

In testimony that I claim the foregoing I have hereunto set my hand, this 1st day of April, 1890, in the presence of witnesses.

JOHN J. BURWELL.
